1,2,3,4-TETRAHYDRO-6-ALKOXY-8-(OMEGA-DIALKYL-AMINO-ALKYL-AMINO) QUINOLINES AND METHOD FOR THEIR PREPARATION

Harry James Barber, Gidea Park, and William Robert Wragg, Cockfosters, England, assignors to May & Baker Limited, Dagenham, England, a British company

No Drawing. Application March 14, 1944, Serial No. 526,474. In Great Britain March 1, 1943

11 Claims. (Cl. 260—288)

1

This invention in a general sense relates to novel chemotherapeutic agents and processes of preparing the same; in a more specific sense, it is concerned with plasmochin-like compounds useful in treating protozoan infections such as malaria, and with processes for obtaining same.

Certain derivatives of quinoline are known to have activity against infections due to protozoan and protozoa-like organisms, for instance malaria. Of this class of compounds plasmochin (Formula 1) and closely related homologs (Formulas 2-4) have heretofore been found most satisfactory.

A disadvantage of these compounds when used as antimalarial agents is that they exhibit substan-

2

tial toxicity toward the human organism, a factor of great importance in view of the long periods of treatment and relatively large dosages necessary to control the protozoan infection.

5 It is now found, pursuant to the present invention, that a class of related compounds possesses antimalarial activity comparable to the quinoline derivatives above mentioned but the compounds, unexpectedly, have materially reduced 10 toxicity. These new compounds are 1:2:3:4-tetrahydro-6-alkoxy-8-(omega-dialkylamino-alkyl-amino)-quinolines which can be represented by the general formula

20 wherein R_1 , R_2 , and R_3 are lower alkyl groups and x is an integer less than 10. Examples are 1:2:3:4-tetrahydro-6-methoxy-8-(omega-dialkylamino-propylamino)-quinolines, 1:2:3:4-tetrahydro-6-methoxy-8-(omega-dialkylamino-butyramino)-quinolines and 1:2:3:4-tetrahydro-6-methoxy-8-(omega-dialkylamino-isopentylamino)-quinolines, specifically the 8-(omega-diethylamino-propylamino), the 8-(omega-diethylamino-butyramino), and the 8-(omega-diethylamino-isopentylamino) compounds.

25 30 35 These new compounds can be prepared in accordance with the present invention by reduction of the corresponding quinoline derivatives using catalytic hydrogenation, preferably with Raney nickel, or by chemical or electro-chemical 40 methods of reduction which are conventional for the quinoline series.

It is also contemplated within the present invention to prepare these novel compounds by methods heretofore employed in manufacture of 45 the corresponding quinoline compounds, with substitution of a tetrahydroquinoline intermediate for the corresponding quinoline intermediate.

The invention further includes preparation of these new compounds by alkaline or neutral reduction of the anils obtained by condensation

of 6-alkoxy-8-amino-quinoline with a ketal of an omega-dialkylamino-alkanone, for instance a suitable ketal of omega-diethylamino-pentanone-2. This reduction can be effected satisfactorily by use of metallic sodium in essentially anhydrous alcoholic solution. Thus, for example, sodium in ethyl or amyl alcohol can be employed. Anhydrous conditions are necessary because the anilines are sensitive to hydrolysis.

Another process within the purview of the present invention for preparing these novel compounds comprises the reaction of 1:2:3:4-tetrahydro-6-alkoxy-8-amino-quinolines in the presence of ammonium chloride or other slightly acidic salt with a compound having one of the following formulae:

wherein R and R₄ are lower alkyl groups or hydrogen atoms, R₁, R₂ and R₃ are lower alkyl groups, and n is an integer more than 2 and less than 10, followed by reduction of the reaction products thus obtained. Catalytic hydrogenation or reduction with sodium in alcohol (for example, ethyl or amyl alcohol) are satisfactory methods for this purpose.

It should be understood that the designations (CH₂)_n and (CH₂)_{n-1} used in this specification and in the appended claims include not only straight chain but also branched chain alkyl groups.

The following examples illustrate methods of carrying out the present invention, but it is to be understood that these examples are given by way of illustration and not of limitation.

Example I

About 174 gm. of 6-methoxy-8-amino-quinoline are reduced catalytically in the presence of 20% Raney nickel at 120° C. and 35 atmospheres pressure using 200 cc. dioxane as solvent. The product, 6-methoxy-8-amino-1:2:3:4-tetrahydro-quinoline, is distilled (B. P. 190°/3 mm.) and stored in an atmosphere of hydrogen.

About 17.8 gm. of 6-methoxy-8-amino-1:2:3:4-tetrahydroquinoline thus prepared, 25.0 gm. of omega-diethylamino-β,β-diethoxy-pentane and approximately 0.2 gm. of ammonium chloride (as catalyst) are heated at a uniform rate from 135° C. to 195° C. over 2 hours with stirring. Practically the theoretical quantity of alcohol is evolved. The product is vacuum distilled, the fraction B. P. 184°/1 mm. which consists of 6-methoxy-8-N-(omega-diethylamino-α-methylbutylidene)-amino-1:2:3:4-tetrahydroquinoline, is stored in an atmosphere of hydrogen.

About 10 gm. of 6-methoxy-8-N(omega-diethylamino-α-methylbutylidene)-amino-1:2:3:4-tetrahydroquinoline obtained in this manner are then dissolved in 50 cc. of anhydrous ethyl alco-

hol in an atmosphere of hydrogen. Approximately 4.5 gm. of sodium are added in small pieces over 1 hour, the reaction being completed by heating on a steam bath under reflux. The product is made acid with concentrated hydrochloric acid, warmed to decompose unreacted anil, filtered to remove salt and the alcohol distilled from the filtrate under reduced pressure. The filtrate is then made basic and extracted with ether.

After evaporation of the ether the product is distilled in an atmosphere of hydrogen and a fraction B. P. 175-180°/1 mm. 6-methoxy-8-N(omega-diethylamino-α-methylbutyl) amino-1:2:3:4-tetrahydroquinoline, is collected. The product is stored in an atmosphere of hydrogen.

Example II

200 gm. of 6-methoxy-8-aminoquinoline is reduced catalytically in the presence of 18% Raney 20 nickel at 130° C. and 40 atmospheres pressure using 200 c. c. dioxane as solvent. The product, 6-methoxy-8-amino-1:2:3:4-tetrahydro-quinoline (B. P. 135°/0.05 mm., 95% yield) is stored in an atmosphere of hydrogen.

25 A mixture of 84.5 gm. of 1:2:3:4-tetrahydro-6-methoxy-8-aminoquinoline, 140 gm. of 5-diethylamino-2:2-diethoxypentane and 1.5 gm. of ammonium chloride are heated at 160-170° C. for 1 hour and then at 170-190° C. for 1/4 hour with 30 vigorous stirring, in an atmosphere of hydrogen. Practically the theoretical quantity of alcohol is evolved. The reaction product, mainly 6-methoxy-8-N-(omega-diethylamino-α-methylbutylidene) 35 amino-1:2:3:4-tetrahydroquinoline is poured quickly into 3 litres of absolutely anhydrous amyl alcohol at 80° C., to which 40 gm. of sodium has just previously been added. A further 120 gm. of sodium is then added and the alcohol refluxed until all the sodium has dissolved. An atmosphere of hydrogen is maintained over the reaction mixture during the following operations. The reaction mixture is made acid to Congo red with concentrated hydrochloric acid and the amyl alcohol 40 removed by steam distillation. The liquors remaining are basified with 50% caustic soda and ether extracted. On removal of the ether the product is carefully fractionated. The fraction, B. P. 175-180°/0.05 mm., 6-methoxy-8-N-(omega-diethylamino-α-methylbutyl) amino-1:2:3:4-tetrahydro-quinoline, in 74% yield, is stored in an 45 atmosphere of hydrogen.

Example III

55 36 gm. of 6-methoxy-8-N-(omega-diethylamino-α-methylbutyl)-amino-quinoline is refluxed with 1.3 litres of anhydrous amyl alcohol and 100 gm. of sodium until all the sodium has dissolved. The reaction scheme may be indicated thus:

An atmosphere of hydrogen is maintained over the reaction mixture during the following operations. The reaction is made acid to Congo red with concentrated hydrochloric acid and the amyl alcohol removed by steam distillation. The 75 product is then dissolved in 50 cc. of anhydrous ethyl alco-

liquors remaining are basified with 50% caustic soda and ether extracted. The product 6-methoxy-8-N-(omega diethylamino-alpha-methyl butyl) amino-1:2:3:4-tetrahydro quinoline, B. P. 175-180°/0.05 mm. is stored in an atmosphere of hydrogen.

These therapeutically useful tetrahydroquinoline compounds, in accordance with the present invention, can be converted into sparingly soluble essentially tasteless salts by reaction with methylene di-beta-hydroxy-naphthoic acid, for instance by the process steps described in British patent specification No. 295,656.

Modifications may be made in carrying out the present invention without departing from the spirit and scope thereof and the invention is to be limited only by the appended claims.

What is claimed is:

1. A composition of matter represented by the formula:

wherein R₁, R₂ and R₃ are of the class consisting of lower alkyl groups and x is an integer less than 10.

2. A 1:2:3:4-tetrahydro-6-alkoxy-8-(omega-dialkyl-amino-alkylamino)-quinoline.

3. A 1:2:3:4-tetrahydro-6-methoxy-8-(omega-dialkyl-amino-propylamino)-quinoline.

4. A 1:2:3:4-tetrahydro-6-methoxy-8-(omega-dialkyl-amino-butylamino)-quinoline.

5. A 1:2:3:4-tetrahydro-6-methoxy-8-(omega-dialkyl-amino-isopentylamino)-quinoline.

6. 1:2:3:4-tetrahydro-6-methoxy-8-(omega-diethyl-amino-propylamino)-quinoline.

7. 1:2:3:4-tetrahydro-6-methoxy-8-(omega-diethyl-amino-butylamino)-quinoline.

8. 1:2:3:4-tetrahydro-6-methoxy-8-(alpha-methyl omega-diethyl-amino-butylamino)-quinoline.

9. The process that comprises the step of reacting a 6-alkoxy-8-amino-quinoline with a sub-

stance selected from the class consisting of compounds of the formulae:

wherein R and R₄ are of the class consisting of lower alkyl and hydrogen, R₁, R₂, and R₃ are lower alkyl, and n is an integer more than 2 but less than 10; and reducing the reaction product to obtain a 1:2:3:4-tetrahydro-6-alkoxy-8-(omega-dialkylamino-alkylamino)-quinoline.

10. The process that comprises condensing a 6-alkoxy-8-amino-quinoline with a ketal of an omega-dialkylamino-alkanone to form an anil intermediate, and reducing this anil intermediate under anhydrous conditions to produce the corresponding 1:2:3:4-tetrahydro-6-alkoxy-8-(omega-dialkylamino-alkylamino)-quinoline.

11. The process that comprises the following steps: catalytically reducing 6-methoxy-8-amino-quinoline to produce 1:2:3:4-tetrahydro-6-methoxy-8-amino quinoline, reacting the reduction product with omega-diethylamino-beta-beta-diepoxy-pentane to produce 1:2:3:4-tetrahydro-6-methoxy-8-(alpha-methyl-omega-diethylamino-butylideneamino)-quinoline, and reducing the reaction product to obtain 1:2:3:4-tetrahydro-6-methoxy-8-alpha-methyl-omega-diethylamino-butylamino)-quinoline.
